H. MAIMIN.
FABRIC CUTTING MACHINE,
APPLICATION FILED JUNE 18, 1915.

Patented June 6, 1916.

UNITED STATES PATENT OFFICE.

HYMAN MAININ, OF NEW YORK, N. Y.

FABRIC-CUTTING MACHINE.

1,186,488.

Specification of Letters Patent.

Patented June 6, 1916.

Application filed June 18, 1915. Serial No. 34,874.

REIQQIUD

To all whom it may concern:

Be it known that I, HYMAN MAININ, a citizen of the United States, and a resident of New York city, in the county of New York and State of New York, have invented certain new and useful Improvements in Fabric-Cutting Machines, of which the following is a specification.

My invention relates to improvements in fabric cutting machines of the type employing a vertically reciprocating knife sliding in a standard, which supports the driving device, usually an electric motor; and the particular mechanism for actuating the knife, together with a protecting guard and presser-foot guide mounted in front of the cutting edge of the knife and capable of a vertically adjustable movement for the purpose of bringing the presser-foot into contact with the top layer of fabric to be cut. The knife is a long flat blade of steel sliding freely in a groove in the forward edge of the standard from which it projects for about one half of its width. It has two cutting edges, the front and the lower. The front edge is known, among those skilled in the art, as the right edge, because an edge of this character is required for cutting which it does with a saw-like motion, as it is pressed against the layers of fabric. This edge is sharpened by the operator by first moving the knife guard out of the way and then by using an emery stick similar to the scythe rifle, and drawing this emery stick downward alternately along each side of the knife at an angle to form the edge. The lower knife edge which is known as the razor edge, because in cutting this edge has the action of a chisel and requires to be extremely sharp, is sharpened by being first removed from the machine and then whetted or honed on a fine grained stone or abrasive device similar to that used for razors.

The objects of my invention are, first to provide a reciprocating knife fabric cutting machine in which the lower or razor knife edge may be sharpened without removing the blade from the machine; second to provide a sharpening device for accomplishing this that will produce a uniform edge of the character required for the correct operation of the machine and third that will save the time necessary for the removal and replacement of the cutting blade.

55 The several objects of my invention as set forth above and the particular methods of

obtaining these are now to be described and are illustrated in the accompanying drawings forming part of this specification.

Similar characters of reference denote like or corresponding parts throughout the several views of which—

Figure 1 is a partial side elevation of a cutting machine of the character described showing my invention; Fig. 2 is a partial rear elevation of the same machine and Fig. 3 is a partial section and front elevation of the operating means for actuating the sharpening device.

Referring particularly to Fig. 1 of the drawings numeral 1 is the base plate or foot plate of the cutting machine. Rising from this plate and secured thereto is the standard 2 the upper portion 3 of which forms a support and guideway into which fits the lower portion 4 of the housing supporting the electric motor 5 and actuating mechanism of the cutting machine. The standard 2 is slotted at its forward edge to a depth corresponding to line 6 and sliding in this slot is a knife 7 the back edge 8 of which normally bears against the bottom of the slot 6. In front of this knife and for the purpose of protecting the operator is a guard 9 secured to the front of the motor housing and capable of vertical adjustment for the purpose of bringing the presser-foot and pattern guide 10 into contact with the upper layer of fabric to be cut. The forward cutting edge 11 of the knife 7 requires a rather rough or saw-like edge for cutting and this is obtained with the use of the emery stick in the manner as described. The lower edge 12 of the knife 7, when this knife is cutting, extends partially inside of the forward edge 13 of the standard so that ordinarily the knife has to be removed from the standard for sharpening this edge; however, with my invention I avoid the necessity of removing the knife by moving the entire driving mechanism and knife mounting forward in relation to the standard so as to bring the entire lower cutting edge 12 beyond the forward edge 13 of the standard 2 and thus expose the edge 12 for sharpening purposes.

The means by which I move the motor and driving mechanism in relation to the standard consists of a hinge portion 14 secured to the base 4 and having helical faced cam surfaces 15 and 16 between which faces is located a cam 17 having faces 18 and 19 shaped similarly to and adapted to co-act with the

faces 15 and 16 respectively. Cam 17 is held in alignment with part 14 by a pin 20 which permits of a swinging rotation of the cam 17 and of the arm 21 preferably formed integral with 17. Cam 17 carries at its central portion a projecting collar 22 which engages in a slot 23 of the upper portion 3 of the standard 2 and serves the purpose of preventing a relative movement between the cam 17 and the standard in the direction of the axis of the pin 20. If the arm 21 is rotated from the position shown in Figs. 1 and 2 in a counter-clockwise direction through 180° it will assume the position 24 shown dotted in Fig. 2 and in this rotation will slide the motor frame 4 backward in reference to the standard and will bring the back edge 8 of the knife 7 into contact with the bottom of the slot 6.

20 The arm 21 carries in a forked end 25, through the pin 27 a short arm 26 capable of moving backward against spring 28 which bears against a projection 29 of a member 31 secured to arm 26. This arm 26 is restricted in its forward movement by the projection 29 coming into contact with a finger 30 secured to arm 21. At the lower end of arm 26 is secured two members 31 and 32. Between these members is pivoted 33 a frame 34 capable of oscillation transversely and at right angles to the plane of movement of arm 26. Journaled in frame 34 at 35 is a shaft 36 secured to one end of which is a crank 37 having a handle 38 by which the shaft may be rotated. The other end of the shaft 36 carries a heart shaped cam 39 adapted to operate between the sides of the fork 40 formed at the lower end of member 32. This cam upon its rotation causes the frame 34 to swing through the arc C D, having about equal periods of movement and rest during one rotation of the shaft; that is, the frame moves from D to C during about 90° rotation of the shaft 36 then remains at rest during the next quarter turn then moves from C back to D during the third quarter period and remains at rest during the fourth quarter period back to the first position mentioned.

50 At the lower end of the frame 34 are projecting pins 41 and 42. The axis of each of these pins is at right angles to the plane of the side of the knife edge 12 on the same side when the frame 34 is in the operative position for grinding either knife face. Mounted on these pins 41 and 42, so as to oscillate thereon, are spools 43 and 44 held on their respective pins by collars 45 and 46. Secured to these spools and extending forward are arms 47 and 48 carrying mounted on their ends and capable of oscillation thereon holders 49 and 50 to which the grinder stones 51 and 52 are secured by any of the well known methods. The holders bear against collars 53 and 54 and are held on the arms 47 and 48 and rotated toward each other by the springs 55 and 56. This rotation however is limited by shoulders 57, 57 against which similar shoulders 59 and 60 on the holders are adapted to engage respectively. The arms 47 and 48 are oppositely reciprocated by a forked lever 61 pivoted to frame 34 at 62 and having forked ends 63 and 64 engaging the arms 47 and 48 respectively. The lever 61 is oscillated back and forward through the rotation of a heart shaped cam 65 secured to shaft 36 and engaging the forked end 66 of lever 61. The cam 65 is so timed in relation to the cam 39 that it serves to oscillate the lever 61 during those periods when the frame 34 is at rest on lines C or D. The cam 65 is further timed to commence an upward movement of arm 47 when the frame 34 has been swung to line D and the grinder stone 51 is in spring contact with the face of edge 12 thus producing by the upward and outward sliding contact of the grinder stone with the edge 12 the correct grinding action. While stone 51 was moving upward in contact with knife edge 12, stone 52 was moving downward and out of contact with the opposite face of edge 12 and upon the continued rotation of the handle 38 after stone 52 reaches its lowest position of travel, the frame 34 will swing to position C, thereby bringing stone 52 into contact with the knife edge 12. For holding the arm 26 in alignment with the standard, projecting fingers 67, 67 are secured to member 32. These fingers engage opposite sides of the standard when the arm 26 and frame 34 are swung from position B¹ to position B, at which time the stones 51 and 52 move past the standard, one on either side of same, into their operative position as shown in Fig. 1. After the knife edge has been sharpened in the manner described, the frame 34 carrying the sharpening mechanism is moved to position B¹ and then the entire sharpening device is rotated to the position 24 where it is held out of the way by the spring catches 68 and 69. This upward swinging movement to position 24 retracts the knife into the standard and leaves the machine in normal operative position.

55 In various ways the details of construction may be modified without departing from the principle involved; the stones may be moved downwardly in contact with the knife edge and different mechanism may be used to accomplish the opposite reciprocation of these stones. Also other cam devices may be used to produce the relative movement between the operative parts of the machine and the standard through the agency of an arm swinging into a position in line with the standard, or the relative movement between the knife and the stand-

ard may be produced by the movement for bringing the stones into the operative position on either side of the knife. I do not therefore wish to be confined to the 5 definite construction described and illustrated herein.

I claim:

1. In a reciprocating knife fabric cutting machine, means for producing a relative 10 movement between the knife and the standard so as to expose the lower edge of the knife for sharpening.
2. In a reciprocating knife fabric cutting machine, means for advancing the knife in 15 the standard to expose the lower cutting edge of the knife for sharpening.
3. In a reciprocating knife fabric cutting machine, means for advancing the knife parallel to its operative position in the 20 standard to expose the lower cutting edge of the knife for sharpening.
4. In a reciprocating knife fabric cutting machine, means for advancing the knife partially from the standard so as to expose 25 the lower edge of the knife for sharpening.
5. In a cutting machine of the character described, means for producing a relative movement between the driving, driven, cutting and protecting elements and the standard 30 ard to permit of the sharpening of the lower edge of the knife.
6. In a cutting machine of the character described, means for advancing the driving, driven, cutting and protecting elements in 35 relation to the standard for exposing the lower edge of the cutting element for sharpening.
7. In a cutting machine of the character described, means for moving the elements 40 supported by the standard in relation to their support for exposing the lower edge of the cutting element to enable the same to be sharpened.
8. In a cutting machine of the character 45 described, means for advancing the elements supported by the standard in relation to their support for exposing the lower edge of the cutting element to enable the same to be sharpened.
9. In a cutting machine of the character 50 described, means for sliding forward the elements supported by the standard in relation to their support for exposing the lower edge of the cutting element to enable the same to be sharpened.
10. In a cutting machine of the character 55 described, means for advancing the knife in the standard to expose the lower cutting edge of the same and sharpening means 60 comprising two abrasive elements adapted to be brought into their operative position,

one on either side of the standard from the back edge of same, for sharpening the lower edge of the knife.

11. In a cutting machine of the character 65 described, means for advancing the knife in the standard to expose the lower cutting edge of the same and sharpening means comprising abrasive elements adapted to be brought alternately into sliding contact 70 with the opposite sides of the lower edge of the knife for the purpose mentioned.

12. In a cutting machine of the character described, means for advancing the knife in the standard to expose the lower cutting 75 edge of the same and sharpening means comprising reciprocating abrasive elements adapted to be brought alternately into sliding contact with the opposite sides of the lower edge of the knife for sharpening same. 80

13. In a cutting machine of the character described, means for advancing the knife in the standard to expose the lower cutting edge of same and sharpening means comprising reciprocating abrasive elements 85 adapted to be brought alternately into sliding contact with the opposite sides of the lower edge of the knife during their upward movement for sharpening same.

14. A reciprocating knife fabric cutting 90 machine comprising a base, a standard rising from the base, a knife reciprocating in the standard, a knife reciprocating motor mounted on the standard and adapted to be advanced in relation thereto by an arm 95 swinging downwardly to a position back of the standard and in line therewith, sharpening means mounted on the arm and arranged to be moved forward into operative position for sharpening the lower edge of 100 the knife.

15. In a cutting machine of the character described having the knife driving elements mounted on the standard and adapted to be advanced in relation thereto by means 105 connected with an arm swinging downwardly to a position back of the standard and in line therewith, sharpening means mounted on the arm comprising two reciprocating abrasive elements capable of forward movement into their operative position, one on either side of the standard, for 110 sharpening the lower edge of the knife by an alternate sliding contact with opposite sides of its edge. 115

Signed at New York city in the county of New York and State of New York this 17th day of June A. D. 1915.
